[57] **CLAIM**

The ornamental design for a condiment shaker, substantially as shown and described.

DESCRIPTION

FIG. 1 is an isometric view taken from above and looking toward the front and one side of the condiment shaker showing my new design;

FIG. 2 is a front view of the condiment shaker;

FIG. 3 is a side view thereof;

FIG. 4 is a top view thereof; and

FIG. 5 is a bottom view thereof.
